UNITED STATES PATENT OFFICE.

LEE BOWERS, OF SHERBURNE, NEW YORK.

HEEL-CALK FOR HORSESHOES.

1,315,080.

Specification of Letters Patent.

Patented Sept. 2, 1919.

Application filed April 12, 1919. Serial No. 289,520.

To all whom it may concern:

Be it known that I, LEE BOWERS, a citizen of the United States, residing at Sherburne, in the county of Chenango and State 5 of New York, have invented certain new and useful Improvements in Heel-Calks for Horseshoes, of which the following is a specification, reference being had to the accompanying drawings.

10 This invention relates to horseshoes, and particularly to heel calks therefor, and more especially to improved means, whereby the calks may be fastened detachably to the shoe.

15 An object of the present invention is the provision of a dovetail groove, which tapers rearwardly, so that every time the shoe comes in contact with the ground the calk is wedged or forced tighter in engagement 20 with the wall of the groove, there being a screw as a precaution to hold the calk in place, and render the same more secure and prevent accidental displacement of the calk forwardly.

25 While the design and construction at present illustrated and set forth is deemed preferable, it is obvious that as a result of a reduction of the invention to a more practical form for commercial purposes, the invention 30 may be susceptible to changes and the right to these changes is claimed, provided they are comprehended within the scope of what is claimed.

The invention comprises further features 35 and combination of parts, as will be herein-after set forth, shown in the drawings and claimed.

In the drawings:

Figure 1 is a bottom plan view of a horse- 40 shoe, showing the toe and heel calks as applied thereto.

Fig. 2 is an enlarged detail perspective view of one of the heel calks looking upwardly.

45 Fig. 3 is a transverse sectional view on line 3—3 of Fig. 1.

Fig. 4 is an enlarged bottom plan view of Fig. 2, showing the walls of the dovetail groove converging toward each other rear- 50 wardly.

Fig. 5 is an enlarged detail perspective view of the toe portion of the shoe looking upwardly.

55 Fig. 6 is a sectional view on line 6—6 of Fig. 5.

Fig. 7 is a cross-sectional view on line 7—7 of Fig. 5.

Fig. 8 is a detail view of the toe calk used in the winter time.

Fig. 9 is a detail view of a heel calk used 60 in the winter time.

Referring more especially to the drawings

1 designates a horseshoe of a conventional 65 design and construction, and 2 denotes the toe calks, which may be constructed either for winter or summer as shown in Figs. 5 and 8. In other words, it is obvious that the ground-engaging portion of either of the calks may be rectangular, or V-shaped, as shown in Figs. 5 and 8. The body of the 70 toe calk is rectangular, that is particularly that part designated by the numeral 3 immediately adjacent the shoe, whereby an ordinary wrench may be easily applied for removing or applying the calks. For instance, it is the aim to provide calks for 75 the toe of a shoe, which may be easily and quickly applied with a wrench of ordinary construction. Projecting from the base of the toe calk is a threaded shank 5, which is 80 threaded into an opening 6 of the shoe, thereby securely fastening the calk in place, that is when the calk is screwed home. It is clear that the toe of the shoe is provided 85 with a pair of calks, and to retain the calks in position, that is to prevent them unscrewing, a retainer plate or an abutment is interposed between the calks. This retainer plate 7 is rectangular, and is secured to the toe of the shoe by means of a screw 8, which 90 passes through the retainer and into a threaded opening 9 of the toe of the shoe. This retainer plate not only retains the calks 95 against accidental rotation or displacement, but also acts as a protector for the calks, particularly since the plate is provided with lateral lugs 10. These lugs 10, it is to be seen, overlie the front walls or faces of the toe calks, thereby not only protecting the bases of the calks, but acting as shields as 100 well as wear elements, and also abutments, to further resist turning of the toe calks.

Each heel portion of the shoe on its under face is provided with elongated flanges, the adjacent walls of which are beveled, 105 These flanges 11 act as retaining members for the heel calk. The adjacent beveled walls 12 converge rearwardly, and by the provision of these flanges and their walls, afford dovetail grooves or recesses 13. Each 110

heel calk 14 has its ground-engaging portion rectangular as shown, and is provided with an integral plate 15. This plate 15 extends forwardly, and is at right angles to the calk. The plate 15 has its edge walls 16 beveled, and said walls converge rearwardly and are designed to engage the beveled converging walls of the flanges. It is obvious, that this heel calk may be arranged 10 between the flanges. In this case, it is apparent that the plate of the heel calk will wedge tighter between the flanges, owing to the successive engagements of the calk with the ground. However, the plate is provided 15 with an opening 18, through which a securing screw 19 passes. This screw also enters a threaded opening of the heel of the shoe. This screw is provided as a precaution against accidental displacement of the 20 calk in a forward direction, due to a force applied at the rear of the calk. It is also to be noted that the head of the screw may be countersunk in the plate, in order to afford a neat construction. Where the plate 25 15 is formed integral with the base of the calk, it is to be noted that the plate is narrower than the base of the calk. In this case, it is to be seen that the opposite sides of the base of the calk as indicated at 30 20 overlie the bottom edges of the flanges, and in this way reinforce the calk in position.

The invention having been set forth, what is claimed as new and useful is:

35 The combination with a heel portion of a horseshoe, the lower opposite corner por-

tions of the heel of the shoe adjacent its extremity having depending elongated flanges, the adjacent walls of which are beveled, said beveled walls converging rearwardly, said flanges near their rear ends being thicker 40 than their forward ends and having their outer faces flush with the outer side edges of the heel of the shoe, of a heel calk V-shaped in cross-section and having a lower sharpened transverse edge, the upper larger 45 end of the calk having an integral plate at right angles to the calk and extending forwardly, said plate being formed across the upper surface of the larger end of the calk and having beveled edges converging rearwardly and adapted to engage and wedge between the converging beveled walls of the flanges, thereby wedgedly locking the plate 50 between the flanges, where the plate is formed across the upper face of the calk, 55 said calk underlying and frictionally engaging the bottom edges of the flanges, thereby reinforcing the connection between the calk and the heel of the shoe, the outer side faces of the calk being flush with the outer side edges of the heel, and means penetrating the plate and the heel between the flanges, to insure holding the plate in wedged engagement between the flanges.

In testimony whereof I hereunto affix my 60 signature in the presence of two witnesses.

LEE BOWERS.

Witnesses:

DUANE L. ATKYNS,
CHARLES THOMPSON.
